BOBBIN STRIPPER

Edgar A. Terrell, Charlotte, N. C., assignor to
The Terrell Machine Company, Charlotte, N. C.,
a corporation of North Carolina

Application September 16, 1931, Serial No. 563,137

24 Claims. (Cl. 28—20)

The invention relates to bobbin-stripers employing scrapers or blades as the principal stripping elements; and especially to improvements in the means adjacent, or associated with the blades, for supporting or locating the bobbins in an initial stripping position, and in proper relation to the blades and other parts of the machine.

A principal feature is the provision of adjustable positioning means cooperating with the bobbin-barrel and head, and also having a cooperative relation to other elements of the machine, to locate the bobbin in proper relation to the stripping blades and other elements which act upon it as it moves to initial stripping position and is moved therefrom in the early stages of the stripping action.

It is of great importance to position the bobbin so that when the scraping blades are advanced toward the barrel they engage in front of the mass 20 of waste thereon, i. e. between the head and the waste, to insure removal of the entire amount of waste. It is likewise of the greatest importance that the bobbin-head shall not enter between the blades, as otherwise breakage of the blades and 25 damage to the bobbins would result through the endwise stripping movement given to the bobbin by the pulling jaws. The present adjustable positioning means provide for such correct and accurate positioning of the bobbin in relation to 30 the blades, and also are readily adaptable to different types of bobbins or to different diameters of bobbin-barrels and heads.

As here shown, the invention features are associated or combined with the stripping blades 35 guide-blocks and other related parts of machines of the types disclosed in U. S. patents to E. A. Terrell, No. 1,740,127 and No. 1,740,128, dated Dec. 17, 1929, but are also adapted or adaptable to other machines of generally similar organization or mode of operation.

As more particularly described with reference to machines of the types referred to, the invention in its broadest aspect contemplates all means which may be adjustably mounted to engage 45 intermediate their ends bobbins of differing dimensions so as to present them properly to the stripping instrumentalities; in its illustrative embodiments it consists in the preferred form of adjustable cover-plates on the scraper-blade 50 guide-blocks, these plates having confronting edge or face formations to receive between them the bobbin-barrel at a point thereon adjacent the head, and also cooperating with the head or the fillet between the head and barrel, to locate the bobbin in proper relation to the strip-

ping blades (or certain of them) and to other elements of the machine. In an alternative form, the whole guide-block and cover-plate assemblies are mounted for adjustment as a unit, carrying with them the bobbin-locating formations. Both 60 forms are fixed in their operative position after being appropriately adjusted.

The characteristics and advantages of the invention are further sufficiently explained in connection with the following detail description of 65 the accompanying drawings, which show a representative embodiment. After considering this example, skilled persons will understand that many variations may be made without departing from the principles disclosed; and I contemplate 70 employment of any structures that are properly within the scope of the appended claims.

In the drawings,—

Fig. 1 is a plan view of a bobbin stripping machine including stripper-blade supporting and 75 guide means embodying the invention in one form, parts of the machine not essential to an understanding of the invention being omitted.

Fig. 2 is a plan view of the two stripper assemblies, enlarged.

Fig. 3 is a plan view of a cover-plate.

Fig. 4 is a plan view of a base- or guide-block.

Fig. 5 is a side elevation of the cover-plate.

Fig. 6 is an end view of one guide-block, with a cover-plate thereon.

Fig. 7 is a front elevation of certain of the parts of Fig. 2.

Fig. 8 shows the bobbin-positioning devices of the invention in combination with alternative head-locating devices.

Figs. 9 and 10 show in plan and end elevation, respectively, an alternative form in which the guide-block assembly is adjusted as a unit.

The invention structure is here shown as included in a stripping machine of general organization substantially as shown in Patent No. 1,740,127 above referred to, a principal characteristic of which is that the bobbin is carried from an initial stripping position through the entire range of stripping movement by a pair of pulling 100 grippers; but it is equally well adapted to machines of the type shown in the other cited patent, No. 1,740,128, a principal characteristic of which in distinction from the one first-mentioned, is that in the stripping action the bobbin 105 is first advanced by a pusher, and such advance is then completed by pulling grippers; or it may be employed where the bobbin is given its movement relative to the stripping blades by a pusher alone as in Patent No. 1,761,695.

Referring now to a machine of the type first above mentioned:—As here sufficiently shown in Fig. 1, this includes main frame side-pieces or rails 1 slidably supporting a pull-head 2 having 5 bobbin-head-gripping jaws 3, with means for reciprocating the head and operating the jaws. At opposite sides of the center line, stripper-blade and bobbin-head positioning means are symmetrically located on the side rails 1, each such means 10 being substantially a unitary assembly, designated as a whole as 4. Bobbins are supplied successively by an arcuate feed-chute located on the side rails (as fully shown and described in the cited Patent No. 1,740,127, and here omitted), 15 the bobbin-head and bobbin-barrel being located between confronting ends of the stripper-blade assemblies; the head is then grasped by grippers 3 and the bobbin is pulled lengthwise a distance greater than its length, to perform the stripping 20 action in a manner fully explained in said patent. In some cases wiper-blades 5 having wiping elements 6 are provided to remove waste which may not be completely removed by the blades. A shutter 7 may also be provided to position the head in relation to the blade assemblies 4 or 25 elements thereof; otherwise when a feed-chute with a guard such as shown in cited Patent No. 1,740,128, or guards of the nature of those forming the subject-matter of my co-pending application Serial No. 558,530, and illustrated in part 30 in Fig. 8, are used (as later referred to) the shutter is omitted. Patent No. 1,740,127 is referred to for a further understanding of the complete organization of the present machine.

35 The two stripper-blade assemblies (Fig. 2), embodying the invention in its first form, are shown in detail in Figs. 2 to 7. These may be substantially identical except for symmetrically reversed shapes or positions of parts on account of location 40 at opposite sides of the machine, and it is sufficient particularly to describe one of them, as follows:

A base- or guide-block 10 has means such as 45 lugs or ears 11 with bolt-holes 12 for securing it to a frame-member 1, and also has vertical spaced side-walls or flanges 13 and 14. Each base- or guide-block has a cover-plate 15 provided with a flange or tongue 16 depending from its under face and located between the side-walls 50 or flanges 13, 14, of the base, and spaced from said walls, as best shown in Fig. 6. Margins of the plate overlie said base walls, and these plate margins have aligned slots 17, elongated in the lengthwise direction of the plate. Screws 18 55 pass through the slots and engage in threaded holes in the base walls, permitting adjustment of the two cover-plates in a lengthwise direction, that is toward and from each other and the center line of the machine. After adjustment, the plate 60 is secured to the guide-block by tightening the screws. A narrow stripping blade 19 is mounted in the guide-channel of rectangular cross-section defined by the cover-plate with its flange 16, the adjacent face of wall 13 and the upper surface 65 of the base, and a relatively wide or thick stripper-blade 20 is similarly mounted in the channel provided between the cover flange and the other base wall 14.

The guide-block has at its inward end a beveled face 22, providing in cooperation with the 70 similar formation on the opposite guide-block a support for the bobbin-head at the side of the stripper-blade assembly adjacent the narrow blades.

75 Preferably, as shown, the inward ends of the

cover flanges or tongues are so formed, as best shown in Figs. 5 and 7, that they are inclined angularly downward and inward, and these faces are also beveled or rounded outwardly away from the vertical side-faces 23 of the tongues, producing edges 24 which slant generally downward and inward; and these edges of the confronting flange ends engage the descending bobbin at opposite sides of the bobbin-barrel, or of the fillet or shoulder connecting the barrel with the inward head face, and thus determine the position of the head through limiting its movement in one direction in the line of the bobbin's axis, and prevent the head entering between the stripping blades. The edges 24 receive the bobbin-barrel 80 between them with a proper slight amount of lateral clearance, the plates being adjusted toward or from each other to regulate their fit or clearance at the sides of the bobbin-barrel or fillet, in accordance with the diameter at these points of the particular kind of bobbin in use. The level to which the bobbin descends from the feed-chute as shown in the above mentioned 85 patents and sufficiently referred to above, is determined by its head, or the head-rings, engaging 90 and coming to rest on the beveled supporting faces 22 of the guide-blocks; while the terminal end or butt of the head is positioned in the axial direction toward the guide-blocks and the barrel-locating or guiding edges 24 of the cover flanges, 95 by the shutter 7 as shown in Fig. 1, and as also disclosed in Patent No. 1,740,127, or by equivalent means such as a finger piece at the lower end of a head-guard-strip associated with the feed-chute, 100 as disclosed in Patent No. 1,740,128, or similar 105 head-locating means such as the auxiliary guard 8 of Fig. 8, associated with a chute-guard structure, as disclosed in my companion application Ser. No. 558,530; or by a movable member on the 110 guard as shown in Patent No. 1,761,695, and such 115 head-locating means may be employed in the machine of Patent No. 1,740,127 with omission of the shutter, as also sufficiently referred to in my co-pending application above.

The bobbin-head, shoulders, and barrel are 120 thus accurately positioned in relation to the stripping blades and especially to the thin blades 19, so that as the blades are moved convergently, their thin, arcuate and rounded edges are caused to move closely adjacent the inward face of the 125 head, or to engage the fillet between the head and bobbin-barrel, so as to insure the edges of the blades engaging properly with the end-portion of the waste carried by the bobbin-barrel 130 as the bobbin is given its relative movement. The bobbins are at the same time properly located in relation to the wide stripping blades 20 which engage and grip the waste at points away 135 from the head. The above-mentioned patents fully disclose means for operating the blades, such means being also sufficiently shown in the present drawings; but detailed description of them is omitted since the construction and arrangement are sufficiently understood by reference to said 140 patents.

The edges 24 of the cover-plates also serve to position the bobbin midway between the opposed blades forming a pair of stripping blades, and permit of adjustment to bring about this desired 145 centered relation.

In the alternative form of the invention illustrated in Figs. 9 and 10 is shown an arrangement in which the opposed bobbin-positioning edges 29 corresponding in function to the edges 24 of the cover-plates just described are formed on tongues 150

or fins 30 integral with the base-portion or guide-block proper 32 of the assembly, just as they were in the patents referred to hereinbefore, but, in distinction from these previous structures, the whole guide-block assembly is mounted on its supports, the side-members 1 of the machine frame, with capacity for adjustment of each assembly as a unit toward and from the middle line of the machine, to permit adjustment of the spaced relation between the opposite guiding edges 29 to position bobbins of different diameters and shapes in the requisite relation with the stripping blades. To provide for such adjustment, the base-portions 32 are provided with slots 34 elongated in the direction of extent of the stripper blades, whereby they may be moved inwardly or outwardly toward and from the middle line of the machine, and secured in adjusted relation through tightening the bolts 36 occupying such slots and passing into the side-members 1. To guide the assemblies during the adjustment, and to maintain them in proper right-angle relation to the bobbin and the side-members, the base-portions 32 are provided with tongues 38 which slide in ways 40 cut for them transversely across the top surface of the side-members 1. This structure has advantages over the adjustable cover-plate structure of Figs. 1 to 8, inclusive, which have been found to make its employment desirable in certain instances.

The invention provides in a simple and economical manner for very accurate adjustment of the bobbin-head and shoulder positioning or locating means such as the opposed edges of the cover-tongues or of the tongues integral with the base-portions, in accordance with the length and diameter of the barrel or the location or radius of the fillet, and without disturbing other parts of the mechanism or interfering with the proper mounting, adjustment or operation of the stripping blades. There is thus provided a distinct improvement and advantage over the structures shown in the above patents, in which the bobbin-head locating or positioning means, formed or arranged as parts of tongues or flanges carried by the fixed guide-blocks, are located in fixed position on the frame-members and adjustment of which is therefore impossible or relatively difficult. In the machines as shown in the patents this adjustment can be effected only by grinding the confronting faces of the base flanges, or providing guide-blocks with flange edge-formations suited for particular types or diameters of bobbin-barrels and heads, and requiring replacement of guide-blocks of which the guiding and positioning faces have become worn in use. As is obvious, in the novel arrangements compensation for wear can be quickly and easily effected, without need for substitution or replacement.

It will now be understood that the present guide-block assemblies may be substituted for the non-adjustable assemblies shown in the other cited Patent No. 1,740,128, thus providing desired adjustability of the bobbin-barrel and head-positioning means, in cooperation with the head-positioning finger on the lower end of the chute-guard-strip, as there shown, or independently movable head-engaging means associated with the guard, as disclosed in my companion application, above identified.

What I claim is:

1. In a bobbin-stripping machine, the combination with stripping means and means for pro-

ducing relative movement between a bobbin and the stripping means in a stripping action, of adjustable means located in operatively fixed position adjacent the stripping means for positioning a bobbin relative to the latter.

2. In a bobbin-stripping machine, the combination with stripping means and means for producing relative movement between a bobbin and the stripping means in a stripping action, of adjustable means at opposite sides of the bobbin when in stripping position to locate the bobbin in relation to the stripping means.

3. In a bobbin-stripping machine, the combination with stripping means and means for producing relative movement between a bobbin and the stripping means in a stripping action, of adjustable means at opposite sides of the bobbin when in stripping position to locate the bobbin longitudinally with respect to the stripping means.

4. In a bobbin-stripping machine, the combination with stripping means and means for producing relative movement between a bobbin and the stripping means in a stripping action, of adjustable means at opposite sides of the bobbin when in stripping position to locate the bobbin longitudinally by cooperation with the fillet joining the head and barrel of the bobbin, and thus to position the bobbin relative to the stripping means.

5. In a bobbin-stripping machine, the combination with stripping means and means for producing relative movement between a bobbin and the stripping means in a stripping action, of means at opposite sides of the bobbin when in stripping position to locate the bobbin longitudinally in cooperation with bobbin-head engaging means, such locating means being adjustable to fit bobbins of different dimensions.

6. In a bobbin-stripping machine, in combination, convergently movable stripping blades, a bobbin-head rest, blade supports, and means adjacent said supports and convergently adjustable to cooperate with a bobbin adjacent its head and position it in relation to the blades.

7. In a bobbin-stripping machine, in combination with means for advancing a bobbin from an initial position for a stripping action, convergently movable stripping blades, a bobbin-head rest, blade-supports, and means adjacent said supports and convergently adjustable to cooperate with a bobbin adjacent its head and position it in relation to the blades.

8. In a bobbin-stripping machine, in combination with means for advancing a bobbin from an initial position for a stripping action, convergently movable stripping blades, blade-supports, and plates adjustably mounted on said supports, having portions cooperating with the bobbin-barrel adjacent the head.

9. In a bobbin-stripping machine, in combination with means for advancing a bobbin from an initial position for a stripping action, convergently movable stripping blades, blade-supports, and plates adjustably mounted on said supports, retaining the blades therein, and having portions cooperating with the bobbin-barrel adjacent the head.

10. In a bobbin-stripping machine comprising in combination means for advancing a bobbin for a stripping action, oppositely-located blade-supports, blades mounted in the supports for convergent movement, and means carried by the supports and adjustable relatively thereto cooperating with a bobbin-barrel at opposite

sides thereof, to position the waste carrying portion of the bobbin in relation to the blades.

11. A bobbin-stripping machine comprising in combination means for advancing a bobbin for a stripping action, oppositely-located blade-supports, blades mounted in the supports for convergent movement, and adjustable means carried by the supports and cooperating with a bobbin-barrel and the inward face of the head at opposite sides thereof, to position the waste carrying portion of the bobbin in relation to the blades.

12. A bobbin-stripping machine comprising in combination means for advancing a bobbin for a stripping action, a bobbin-head rest, oppositely-located blade-supports, blades mounted in the supports for convergent movement, and members mounted on said supports for convergent and divergent adjustment and having confronting downwardly convergent face-formations located at opposite sides of the bobbin-barrel in initial stripping position.

13. A bobbin-stripping machine comprising in combination means for advancing a bobbin for a stripping action, oppositely-located blade-supports, blades mounted in the supports for convergent movement, and members mounted on said supports for convergent and divergent adjustment and having confronting downwardly convergent edge-formations located at opposite sides of a bobbin-barrel in initial stripping position and cooperating with the barrel and head to position the bobbin in relation to the stripping blades.

14. A bobbin-stripping machine comprising in combination means for advancing a bobbin for a stripping action, supports located on opposite sides of the bobbin when the latter is in stripping position, stripping blades mounted for convergent movement, and members operatively fixed on said supports for having capacity for relative convergent and divergent adjustment and having confronting face-formations cooperating with the bobbin-barrel to locate the bobbin in relation to the blades.

15. A bobbin-stripping machine comprising in combination means for advancing a bobbin for a stripping action, oppositely-located blade-supports, blades mounted in the supports for convergent movement, and cover-plates mounted on said supports for relative convergent and divergent movement, the plates having depending flanges cooperating with the blades to locate and guide them, the flanges having at their inward ends, downwardly convergent formations cooperating with the bobbin-barrel and head or fillet to locate the bobbin in relation to the blades.

16. A stripping blade and bobbin supporting assembly for a bobbin-stripper comprising in combination a guide-block, a cover-plate adjustably mounted thereon and having a flange extending between side-walls of the block and providing between it and said walls guide-channels for stripper blades mounted therein, the flange having at its inwardly directed end a downwardly and inwardly inclined face-formation to cooperate with a bobbin-barrel and head or fillet.

17. A stripping blade and bobbin supporting assembly for a bobbin-stripper of the general character described, said assembly comprising a guide-block having spaced side-walls, a cover-plate overlapping said walls and provided with slots, screws passing through the slots and engaging in the walls for adjustment of the cover-plate toward and from the bobbin when the latter is between the blades, the plate also having a flange located between the block walls and spaced there-

from, the flange having at its inwardly directed end an edge-formation inclined downwardly-inward for cooperation with a bobbin-barrel and head.

18. In a bobbin-stripper, the combination with 80 opposed stripping blades that close upon the bobbin, bobbin-head guiding and supporting means, and means for presenting a bobbin within range of such blades, of means for centering the bobbin with respect to the blades in advance of its engagement with the blades, adjustable to accord with the varying diameter of different bobbins.

19. In a bobbin-stripper, the combination with 90 opposed stripping blades that close upon the bobbin, bobbin-head guiding and supporting means, and means for presenting a bobbin within range of such blades, and means for determining the presentation position of the bobbin in a plane at right angles to the direction of movement of the blades, of means for determining the presentation position of the bobbin in the plane of movement of the blades, adjustable to accord with the varying diameters of different bobbins.

20. In a bobbin-stripper, in combination, means 100 for advancing a bobbin into stripping position, a bobbin-head rest, opposed stripping blades having bobbin-engaging surfaces conforming to the contour of the bobbin-barrel, devices centering the advanced bobbin with respect to the blades and also positioning the bobbin lengthwise with 105 respect to the blades, and adjustable to suit the shapes of different bobbins.

21. In a bobbin-stripping machine, in combination with means for advancing a bobbin from 110 an initial position for a stripping action, convergently movable stripping blades, blade-supports, and means adjacent said supports and convergently adjustable to cooperate with a bobbin head and the portion of the barrel closely adjacent its head and position it in relation to the 115 blades and also in relation to a positioning member cooperating with the bobbin-head.

22. A bobbin-stripping machine comprising in combination means for advancing a bobbin for a 120 stripping action, oppositely-located blade-supports, blades mounted in the supports for convergent movement, and adjustable means carried by the supports and cooperating with a bobbin-barrel and the fillet between the barrel and head 125 at opposite sides of the bobbin, to position the waste carrying portion of the bobbin in relation to the blades.

23. A bobbin-stripping machine comprising in combination means for advancing a bobbin for 130 a stripping action, blade-supports on opposite sides of the bobbin when in initial stripping position, blades mounted in the supports for convergent movement, and members operatively fixed on said supports with capacity for convergent 135 and divergent adjustment and having confronting face-formations located at opposite sides of the bobbin-barrel in initial stripping position.

24. A bobbin-stripping machine comprising in combination means for advancing a bobbin for 140 a stripping action, oppositely-located blade-supports, blades mounted in the supports for convergent movement, and cover-plates mounted on said supports for relative convergent and divergent movement and having confronting face-formations cooperating with the bobbin barrel to locate the bobbin in relation to the blades, said plates retaining the blades in position in the supports.
